(72) Inventors: **Richard Carey**, Manitowoc, WI (US); **Ross Niemi**, Sheboygan, WI (US)*Primary Examiner* — Terry A Wallace(73) Assignee: **The Metal Ware Corporation**, Two Rivers, WI (US)*(74) Attorney, Agent, or Firm* — Seager, Tufte & Wickhem LLP.(**) Term: **15 Years**(57) **CLAIM**(21) Appl. No.: **29/608,075**

The ornamental design for a cooler, as shown and described.

(22) Filed: **Jun. 19, 2017****DESCRIPTION**(51) **LOC (11) Cl.** **07-01**

FIG. 1 is a top perspective view of a cooler showing our new design.

(52) **U.S. Cl.**

FIG. 2 is a front view thereof.

USPC **D7/605**

FIG. 3 is a rear view thereof.

(58) **Field of Classification Search**

FIG. 4 is a right side view thereof.

USPC D7/603–608, 709; D3/272–274

FIG. 5 is a left side view thereof.

CPC ... A45C 11/20; A45C 9/00; F25D 3/14; F25D

FIG. 6 is a top plan view thereof.

3/08; F25D 3/12; B65D 81/3813; B65D

FIG. 7 is a bottom plan view thereof.

81/3823; B65D 81/3888; B65D 81/3889;

FIG. 8 is a top perspective view thereof with the latches in a released position.

B65D 81/3816; B65D 81/3858; F24D

FIG. 9 is a front view thereof, with the latches removed for clarity of illustration.

2331/804; A47J 41/022; A47J 41/00;

FIG. 10 is a top perspective view of an alternate embodiment of FIG. 1.

A47J 45/06; A47G 19/2288; F25B 19/00

FIG. 11 is a front view of FIG. 10.

See application file for complete search history.

FIG. 12 is a rear view of FIG. 10.

(56) **References Cited**

FIG. 13 is a right side view of FIG. 10.
